(57) **CLAIM**

The ornamental design for a shoe support, as shown and described.

DESCRIPTION

FIG. 1 is an exploded perspective view of a shoe support showing my new design, with a shoe shown in broken lines positioned above the support;

FIG. 2 is another perspective view thereof, with a shoe shown in broken lines in a used condition;

FIG. 3 is a right side elevational view thereof;

FIG. 4 is a left side elevational view thereof;

FIG. 5 is a bottom plan view thereof;

FIG. 6 is a top plan view thereof;

FIG. 7 is a back elevational view thereof; and,

FIG. 8 is a front elevational view thereof.

The shoe shown in broken lines in FIGS. 1 and 2 form no part of the claimed design.
